UNITED STATES PATENT OFFICE.

LOUIS COEN, OF VICTORIA, LONDON, ENGLAND.

SMOKE-FILTER FOR CIGARETTES.

1,070,412.

Specification of Letters Patent. Patented Aug. 19, 1913.

Application filed April 25, 1911. Serial No. 623,198.

To all whom it may concern:

Be it known that I, LOUIS COEN, of 316 Vauxhall Bridge road, Victoria, London, England, cigarette manufacturer, have invented new and useful Improvements Relating to Smoke-Filters for Cigarettes; and I do hereby declare that the following is a full, clear, and exact description of the same, reference being had to the accompanying drawings, forming a part hereof.

This invention has reference to improvements in or relating to means for filtering or purifying smoke passing through cigarettes, cigars and the like and has for its object to do away to a large extent with the evils attending the habit of smoking.

In carrying my invention into practice I employ a piece of linen or silk as the filtering medium which may be stiffened or not as desired and which can be inserted as a disk for example in such a manner that the smoke must pass through same in order to enter the mouth. Means are also provided whereby the linen or like filtering material is retained in position. In all forms of my invention the filter is placed about $\frac{1}{8}$ th (one eighth) of an inch from the end of cigarette or cigar thus preventing the juice of the tobacco from touching the tongue or lip. And in order that my invention may be readily understood and carried into effect I will now proceed to describe the same fully for which purpose reference is to be had to the accompanying drawings in which:—

Figure 1 is a sectional view of my invention as applied to cigarettes. Fig. 2 illustrates my invention as applied to cigars.

In all the figures the parts are exaggerated in size in order to better illustrate the invention.

Referring now to the invention as shown in Fig. 1 *a* indicates the filling of tobacco and *b* a cigarette paper which as shown envelops the cardboard mouth piece *c*. The filtering material which may be of linen

silk or other appropriate fabric either stiffened or not as may be desired is placed over the open mouth piece end of the cigarette and a cardboard or other ring *d* is then placed upon the disk of filtering material. The disk and ring are then pushed into the mouth piece by an appropriate instrument thus causing the filtering material to take up the position shown in Fig. 2, the cardboard ring acting to retain the fabric *e* in position.

Of course it will be understood that the arrangement above described may be reversed that is to say the ring *d* may be placed on the other side of the filtering material in which case the said filtering material will assume the reverse position as shown by the dotted lines in Fig. 1.

In applying my invention to cigars, an example of which is shown by Fig. 2 the filling *a* is first rolled and a cardboard tube *c* containing the filtering medium *e* is then placed over the end of the cigar. The outer covering or leaf *f* is then arranged and secured in position thus holding the mouth piece containing the filter securely in position.

What I do claim as my invention and desire to secure by Letters Patent is:—

The combination with a tobacco like filler; of a wrapper surrounding said filler and projecting beyond the same at the mouth end, a tubular reinforcement held wholly within the projecting portion to leave a smooth unbroken exterior on said wrapper, and a drum consisting of a ring covered on one end and the sides with filtering fabric, said drum being positioned in said reinforcement with the fabric in spaced relation to the mouth end of the wrapper.

In testimony whereof I affix my signature in presence of two witnesses.

LOUIS COEN.
